UNITED STATES PATENT OFFICE.

LOUIS CARROLL STUKENBORG AND GEORGE H. HANDY, OF CHICAGO, ILLINOIS, AS
SIGNORS, BY MESNE ASSIGNMENTS, TO STUKENBORG CORPORATION, OF WILMING-
TON, DELAWARE, A CORPORATION OF DELAWARE.

COTTON PICKER.

Application filed October 3, 1919. Serial No. 328,972.

To all whom it may concern:

Be it known that we, LOUIS CARROLL STUKENBORG and GEORGE H. HANDY, citizens of the United States, and residents of Chicago, in the county of Cook and State of Illinois, have invented certain new and useful Improvements in Cotton Pickers; and we do hereby declare that the following is a full, clear, and exact description thereof, 10 reference being had to the accompanying drawings, and to the characters of reference marked thereon, which form a part of this specification.

This invention relates to improvements in 15 cotton picking machinery, and refers more particularly to improvements in the picker mechanism which directly engages the cotton boll to remove the fibre from the plant.

The object of the invention is to improve 20 and simplify cotton picker mechanisms of that type embracing brushes which directly engage the bolls to remove them backwardly into a picker head, from which the cotton is carried rearwardly in any suitable 25 manner; as by a blast of moving air induced by a suction device.

In the drawings, is shown a number of practical adaptations of the invention, each 30 of which embraces a series of rotative brush elements and a shell having openings through which the brush elements are movable, said shell and the series of brush elements being mounted to rotate on axes that are eccentric in respect to each other to extend 35 the brush elements outwardly at the front of the head for free contact with the cotton bolls and to withdraw the brush elements into the shell as the shell is rotated so as to remove the cotton dislodged from 40 the burs. The combined stripping means and the brush elements thus constitute a unitary picking and stripping device for removing the cotton from the burs and carrying it back and delivering it into the path 45 of a rearwardly moving blast of air. In addition to the stripping means afforded by the eccentric relation of the shell and brush elements, stationary doffers or combs may, if desired, be applied to act on the bristles 50 of the brushes during the time they are disappearing into the shell.

In the drawings:

Figure 1 is a vertical, longitudinal section of a picker mechanism embodying our invention. 55

Figure 2 is a transverse section on the line 2—2 of Figure 1.

Figure 3 is a perspective view of one of the brush holders.

Figure 4 is a perspective view of one of 60 the brush elements.

Figure 5 is a section similar to Figure 2, showing a modification.

Figure 6 is a fragmentary plan view of the stripper shell shown in Figure 5. 65

Figure 7 is a longitudinal section illustrating a further modification.

First, referring to the construction shown in Figures 1 to 4, inclusive, 10 designates a head of suitable formation to contain and 70 support the picker mechanism. It is formed at its front end with a forwardly opening mouth 11 and is tapering at its rear end to form a neck 12 to which is adapted to be attached a suction tube 13. The picker 75 mechanism embodying my invention is located at the front or mouth of the head and is made as follows:

14 designates a shell which is disposed with its axis transverse to the mouth of 80 the head. One end of the shell is mounted on an exteriorly facing cylindrical bearing 15 which, as herein shown, comprises a block 15' that is riveted or otherwise fixed to the casing and extending into said shell. Within 85 the other end of the shell is a driving disc 16 which is formed integral with a short driving shaft 17 that is mounted in a bearing member 18 fixed to or made integral with the wall of the head. The head may 90 be made of cast metal or may be made of stamped metal, and in either event the bearing members 15' and 18 may be made integral with the head if desired. The driving shaft 17 has a worm gear 19 which meshes 95 with a worm driving gear 20, that may be connected through suitable gears, to a source of driving power, as a motor, mounted on the head or on the frame of the machine in rear of the head. The shell 14 is formed 100 with a plurality of longitudinal slots 22 of which there may be any suitable number.

As herein shown, the shell comprises an outer relatively heavy member 23, which may be made of relatively soft material, such as brass, fibre, or the like, and an inner thin member 24, made preferably of a hardened steel. If the shell be so formed the inner and outer members may be fastened together by screws 25 which extend outwardly through the inner thin shell member and 10 into the outer member. When so constructed, the screws may be locked in place and a driving connection afforded between the driving disc 16 and shell by providing said disc 16 with a series of angularly spaced 15 notches 26 to receive the heads of said screws. If the shell be made of a single or integral casting the driving connections may be afforded between the shell and the disc 16 by projections on the shell, corresponding to 20 the screw heads, and engaging the notches 26 of the driving disc 16.

28 designates a shaft within the shell and is eccentric to the axis of rotation of the shell. As herein shown, it is fixed to or 25 made an integral part with the bearing member 15' and extends longitudinally through the shell parallel to the axis of rotation of the latter and terminates short of the driving disc 16. Rotatively mounted 30 on said shaft 28 is a sleeve 29, coextensive in length with the shaft. 30, 30 designate a plurality of elongated brush holders, each arranged opposite to one of the slots 22 of the shell. All but one of said brush holders 35 are hinged at their inner sides to said sleeve 29. As herein shown, said sleeve is formed with a plurality of angularly spaced elongated notches 32 in which the inner sides of the brush holders fit, and said holders 40 are connected to the sleeve by means of pins 33 which extend through openings in the sleeve at the ends of the notches and through registering openings 34 in the inner sides of the brush holders. One of the notches 45 32 is squared or otherwise formed to fixedly hold one of the brush holders relatively thereto so that said latter holder becomes a driving connection between the shell and sleeve, whereby the latter is rotated by the 50 former. The other notches have rounded bottoms so that the brush holders seated therein can have a swinging or hinge movement relatively to the sleeve. 35 designates a plurality of brush backs, each consisting 55 of an elongated bar 36 and a series of bristles 37. The bars 36 are adapted to slide endwise into grooves 38 formed in the outer sides of the holders, the grooves and bars being interlocked in any suitable manner to 60 avoid radial displacement of the brush elements, as, for instance, by undercutting the grooves and correspondingly forming the 65 bars.

The eccentricity of the shaft 28, on which the brush element sleeve 29 is mounted, rela-

tively to the axis of rotation of the shell 14 is such that when the shell is rotated, thereby rotating the said sleeve, the bristles of the brush elements at one side of the shell are projected from the shell for contact with the cotton bolls, while the bristles of other brush elements are partially or wholly drawn within the shell, the bristles at the rear of the shell being practically flush with the outer face of the shell, so as to permit 75 the cotton to be stripped from the bristles by the rearwardly moving air blast in the head. The said holders 30, or parts thereof, may be made of hard metal similar to the hard metal member 24 of the shell, and in 80 order to avoid wear between the holders and the softer metal member 23 of the shell, the said radial openings 22 are formed with the outwardly and laterally flaring clearance recesses 40 only of such width and so 85 arranged that the only contact between the brush holders and shell is at the inner narrow sides of the radial grooves of the shell.

In operation, driving power is delivered to the picker mechanism through the shaft 17 to rotate the shell 14 and driving power is communicated from said shell through one of the brush holders to drive or rotate the sleeve 29 and therethrough the series of brush holders and cause the brush elements 95 as a series to rotate about the axis of the shaft 28, so that thereby the bristles which tip the brush elements are caused to be projected from the shell at the front of the picker mechanism for engagement with the 100 cotton bolls to detach the latter from the plants and to be gradually withdrawn into the shell as the shell rotates rearwardly, as indicated in Figure 1. The picker head casing is preferably provided in rear of its 105 mouth with one or more air openings 43 so proportioned that the larger part of the air passing through the head, due to the suction device in rear thereof, enters the head through said port or ports 43 and is directed 110 against the part of the shell into which the bristles are being withdrawn at the rear of the shell. The picker head casing is so proportioned as to produce a passage 43' of ample width between the casing and the 115 ends of the bristles for the entrance of cotton backwardly into the casing. Preferably the bristles of the brush element are comparatively stiff so that the cotton may be carried backwardly into the head without 120 materially bending the bristles. If desired and found necessary, a stationary comb or doffer 45 may be fixed to the casing in rear of the shell with the teeth 46 thereof in position to strip cotton which may tend to cling 125 to the bristles before complete withdrawal of the bristles into the radial slots.

In order to prevent the burs of the plants being carried into the head, suitable guards 130 may be arranged in front of the picker

mechanism and connected to the casing head above the mouth in any suitable manner, as by being attached to a cross bar 48 that is fixed to the head. Shorter guards 49 5 may be also carried by the head casing at the other side of the mouth.

The arrangement of the slotted holders 36 to receive the brush backs 35 enables the latter to be removed endwise from the slots 10 38 of said holders when the bristles are worn and other brush elements are to be inserted thereinto. Any suitable locking means 15 may be provided for locking the brush backs from endwise displacement in said holders. For instance, the portions of 20 the holders bounding the recesses 38 may be made of sheet metal capable of springing outwardly a limited distance, and the ends of said walls at one end of the holder 25 may be provided with inturned lugs 50 to engage notches 51 at the corresponding ends of the bars 36. The said bristle carrying backs or bars may be endwise removed from the holder slots at a time when the brush 30 elements are furthest projected from the shell 14 and new bristle carrying backs or bars inserted, as shown in Figure 1.

In the construction shown in Figure 7 35 two rotating oppositely acting, picker means, embracing the rotative, relatively eccentric shells and series of picker elements, are employed, in which event the plural picker means rotate inwardly toward each other in the direction indicated 40 by the arrows in said Figure 7. In the construction shown in said Figure 7, two sets of guards 52 are employed which extend across the mouth, being attached to the head at the opposite sides of the mouth, 45 and extending towards each other. In the latter construction driving power is communicated to one of the rotary picker devices, and the other may be driven therefrom by direct gearing.

45 In the construction shown in Figures 5 and 6, the brush elements comprise a plurality of sets of radial pins 55 which are connected at their inner ends to the sleeve 29 and are tipped at their outer ends by 50 bristle tufts 56 which are adapted to be projected outwardly from and withdrawn into the shell 14 through a series of openings 57 in the shell when the latter and the sleeve 29 are rotated, said openings having 55 outwardly flaring clearance recesses 58 similar to the recesses 40 of the previously described construction. In other respects the construction shown in said Figures 1 and 6 is like that shown in Figures 1 to 4 inclusive.

60 In all of the constructions described, it will be observed that the picker mechanism by which the cotton is removed from the burs and carried backwardly into the head 65 and discharged from the brushes into the

rearwardly moving air blast is a unitary construction, so that thereby the driving mechanism for the picker mechanism is simplified. Moreover, by reason of the unitary relation of the cotton picking and 70 stripping mechanism by which the cotton is removed from the bristles of the brush elements, the picker head is compact and the weight thereof is reduced as compared to prior cotton picker mechanism. 75

It will be understood that the structural details of the mechanism may be somewhat varied from that shown within the spirit and scope of the appended claims and that the invention is not limited to the illustrated embodiments except as to claims wherein structural details are specifically set forth and as imposed by the prior art. 80

It will also be understood that the proportions of the mechanism in respect of 85 actual dimensions of parts and relative dimensions thereof are also capable of considerable variation.

We claim as our invention:

1. A cotton picker comprising a rotative 90 series of bristle brushes adapted for contact with cotton bolls, a rotative member to which said brushes are connected to advance the brushes toward and cause them to recede from picking positions, and hollow 95 rotative stripper means enclosing and axially eccentric to and co-operating with the moving brushes to strip the cotton therefrom.

2. Cotton picker mechanism embracing a 100 head, having a mouth, groups of interacting angularly spaced picker elements revoluble as a series about an axis extending across said mouth, said elements being tipped by bristles, and a rotative stripper element 105 enclosing said axis and having openings through which said picker elements extend, with its axis of rotation parallel with and eccentric to the axis of revolution of said picker elements. 110

3. Cotton picker mechanism embracing a head, having a mouth, a pair of co-operating bristle tipped picker elements revoluble on parallel axes within said mouth, and stripper elements partially enclosing and co-operating with the moving picker elements to cause the picker elements to be projected from and recede into said stripper elements. 115

4. A cotton picker comprising a rotative, cylindrical shell having radial openings, bristle tipped brush elements rotative on an axis within and eccentric to the axis of rotation of said shell and movable outwardly and inwardly through said openings, and doffing means exterior to said shell and co-operating with said brush elements. 120

5. A cotton picker comprising a rotative, cylindrical shell having radial, outwardly flaring openings, bristle tipped 125

- brush elements rotative on an axis within and eccentric to the axis of rotation of said shell and movable through said openings.
- 5 6. A cotton picker comprising a rotative, cylindrical shell having radial openings, brush holders movable through said openings, and bristles removably seated in said holders, said brush holders being rotative about an axis within and eccentric to the axis of rotation of said shell.
- 10 7. A cotton picker comprising a rotative cylindrical shell having elongated radial openings, brush elements movable through said openings, comprising slotted holders, and brushes seated in and removable endwise from the slots of said holders, said holders being rotative about an axis within and eccentric to the axis of rotation of said shell, whereby the brushes are movable through the openings of said shell.
- 15 8. A cotton picker comprising a rotative cylindrical shell having elongated radial openings, brush elements movable through said openings, comprising slotted holders, and brushes seated in and removably endwise from the slots of said holders, said holders being rotative about an axis within and eccentric to the axis of rotation of said shell, and means to lock said brushes in said holders.
- 20 9. A cotton picker comprising a rotative, cylindrical shell having elongated radial openings, brush elements movable through said openings, comprising slotted holders, and brushes seated in and removable endwise from the slots of said holders, with means to lock said brush elements from radial and endwise displacement in said holders, said holders being rotative about an axis within and eccentric to the axis of rotation of said shell, and means to lock said brushes from endwise movement in said holders.
- 25 10. A cotton picker comprising a rotative, cylindrical shell having elongated radial openings, brush elements comprising holders having slots bounded by springable walls, and brushes seated in and removable endwise from said slots, said holders being rotative about an axis within and eccentric to the axis of rotation of said shell and interlock-
- ing connections between said springable walls and said brushes.
11. A cotton picker comprising a rotative, cylindrical shell having radial openings, means to rotate the shell, a fixed shaft within and eccentric to the axis of rotation of said shell, a sleeve rotative on said shaft, and bristle tipped brush elements movable through said openings and connected to said sleeve. 55
12. A cotton picker comprising a rotative, cylindrical shell having radial openings, means to rotate the shell, a fixed shaft within and eccentric to the axis of rotation of said shell, a sleeve rotative on said shaft, and brush elements movable through said openings, and connected to said sleeve, one of said brush elements constituting a driving connection between said shell and said sleeve. 60
13. In a cotton picker, a casing, a cylindrical shell therein provided with radial openings, a cylindrical bearing on the casing wall on which one end of the shell is rotatively mounted, a disc within and non-rotatively interlocked to said shell, a driving shaft rigid with said disc and rotatively mounted in said casing, and a series of radial members movable through the shell openings and rotative about an axis within and eccentric to the axis of rotation of said shell. 65
14. In a cotton picker, a casing, a shell therein provided with radial openings, a cylindrical bearing on the casing wall on which one end of the shell is rotatively mounted, a disc within and non-rotatively interlocked to said shell, a driving shaft rigid with said disc and rotatively mounted in said casing, and a series of radial members movable through the shell openings and rotative about an axis within, and eccentric to the axis of rotation of, said shell, said shell comprising inner and outer members with means for fastening said members together and constituting parts of the interlocking connection between said shell and said disc. 70
15. In witness whereof we claim the foregoing as our invention, we hereunto append our signatures this ninth day of September, 1919.
- LOUIS CARROLL STUKENBORG.
